Primary Examiner — Karen E Eldridge Powers(74) Attorney, Agent, or Firm — Marc E. Hankin; Kevin Schraven; Jimmy Sauz(57) CLAIM

The ornamental design for a hood, as shown.

DESCRIPTION

FIG. 1 is an illustration of a top perspective view of a hood showing my new design.

FIG. 2 is an illustration of a top plan view thereof.

FIG. 3 is an illustration of a bottom perspective view thereof.

FIG. 4 is an illustration of a bottom plan view thereof.

FIG. 5 is an illustration of a rear elevation view thereof.

FIG. 6 is an illustration of a front elevation view thereof.

FIG. 7 is an illustration of a left side elevation view thereof; and,

FIG. 8 is an illustration of a right side elevation view thereof. The broken lines shown in the drawings are stitch lines and form a part of the claimed design.
